UNITED STATES PATENT OFFICE.

FRANK A. FOX, OF NEW YORK, N. Y., ASSIGNOR TO THE STEELE & JOHNSON MANUFACTURING COMPANY, OF SAME PLACE.

BUTTON.

SPECIFICATION forming part of Letters Patent No. 363,628, dated May 24, 1887.

Application filed February 21, 1887. Serial No. 293,342. (No model.)

To all whom it may concern:

Be it known that I, FRANK A. FOX, of New York, in the county and State of New York, have invented a certain new and useful Improvement in Buttons, of which the following is a specification.

My improvement relates to uniform-buttons, such as those worn by conductors, yachtsmen, &c., and which are adapted to be slipped over an ordinary or a plain button and removed when desired.

I am aware that heretofore such a uniform-button has been made of a cap or shell provided with a fixed section of back-plate and a sliding section of back-plate, which latter could be adjusted after the cap or shell had been placed over an ordinary button, so as to extend over the back of the latter and secure the cap or shell in place thereon.

The great objection to the uniform-buttons of the kind I have above described is that they have been necessarily loose upon the ordinary buttons when made large enough to be capable of being easily applied to and removed from the same. This objection has very materially interfered with the use of these uniform-buttons.

The object of my present improvement is to obviate the difficulty in the above-described uniform-buttons to which I have called attention.

The improvement consists in a button-cover adapted to wholly receive a button, and having at the rear side a fixed back section and a sliding back section, and being provided on the inner side with a spring or bar to press against the button and hold it firm.

In the accompanying drawings, Figure 1 is a back view of a uniform-button embodying my improvement. Fig. 2 is a similar view showing a sliding section of the back in a different position. In both these figures the bar or spring which I have previously mentioned is represented in dotted outline wherever it lies behind other parts. Fig. 3 is a view similar to Fig. 1, showing a modification consisting in the substitution of a bar for a spring. Fig. 4 is a transverse section of a uniform-button embodying my improvement and of an ordinary button to which said uniform-button is applied.

Similar letters of reference designate corresponding parts in all the figures.

A designates an ordinary button. As represented, this button is of a type commonly made from guita-percha, bone, or like material. It has a number of holes through which thread may be passed for securing the button to a garment.

B designates my uniform-button, which consists of a cap or shell, preferably made of sheet metal, ornamented and marked to suit the taste or requirements of the user, and having at the rear a fixed back section, b, and a sliding back section, b'. The fixed back section may advantageously be made integral with a ring, b², fitted into the rear portion of the cap or shell. The sliding back section may be fitted into a groove in the ring b², which is made integral with the fixed back section, b. Thus provision will be conveniently afforded for adjusting the sliding back section circularly. The fixed back section, b, is shown as made approximately crescent shape, and the sliding back section is represented as of the same shape. The sliding back section is provided on the outer side with a small projection, b³, which serves as a handle by means of which the sliding back section can be conveniently manipulated, and also has a stop to limit the movements of the sliding back section. The sliding back section can be moved into a position just inward of the fixed back section, so as to occupy a position in line therewith and leave a large opening, whereby the uniform-button can be applied and removed with facility; or the sliding back section may, after the application of the uniform-button to the ordinary button, be adjusted into a position opposite the fixed back section, so as to secure the uniform-button in place.

C designates a spring or bar. As shown in Figs. 1, 2, and 4, a spring consisting of a strip of sheet metal is employed. In Fig. 3 a bar, which may be of metal or other material, is shown.

The spring or bar will preferably be arranged in such position that it will be opposite the opening left between the fixed back section and the sliding back section when the latter is adjusted into a position opposite to the fixed back section. The uniform-button

may be applied by slipping it over and pressing it against the ordinary button, and when the spring C is used the latter may yield to facilitate the application of the uniform-button, 5 and, after the adjustment of the sliding back section of the uniform-button, will serve to hold the uniform-button without rattling.

When the bar C is used, the latter may serve as a sort of a rocking support upon which the uniform-button may rock in being applied to the ordinary button. As it admits of this rocking action, it will allow of the application of the uniform-button easily, and yet will hold it against rattling after it shall have been applied.

What I claim as my invention, and desire to 15 secure by Letters Patent, is—

A button-cover adapted to wholly receive a button, and having at the rear side a fixed back section and a sliding back section, and being provided on the inner side with a spring 20 or bar to press against the button and hold it firm, substantially as specified.

FRANK A. FOX.
